UNITED STATES PATENT OFFICE.

AUGUST HERMANN MEYER, OF PLAUEIN, GERMANY.

DEVICE FOR THE PRODUCTION OF CROCHET SEAMS AND PATTERNS IN EMBROIDERY MACHINES.

Application filed September 22, 1921. Serial No. 502,507.

To all whom it may concern:

Be it known that I, AUGUST HERMANN MEYER, a citizen of the Republic of Saxony, residing at Plauen, in the Republic of Saxony, Germany, have invented certain new and useful Improvements in Device for the Production of Crochet Seams and Patterns in Embroidery Machines, of which the following is a specification.

10 This invention relates to embroidery machines for the manufacture of crochet seams and especially to a device for the formation of stitches in embroidery machines serving for the production of crochet seams and crochet patterns.

As is well known the characteristic feature of such crochet embroidery machines consists in the compound operation of two endless threads, of which one is used at the 20 front side and the other at the back side of the fabric for stitch formation. The front thread is conducted by embroidery needles of known construction into the fabric, while the same number of hook shaped needles or 25 catches are provided instead of shuttles at the back part of the fabric adapted to form an endless back thread to a loop, respectively and lock the front thread by pulling it through.

30 In the present invention a new improvement is provided by the fact that the parts designed to close the latches of the hook shaped catches, to wit the so-called latch compressors, also are provided with thread-guiding eyes and that these latch compressors, contrary to the present construction, which perform only a movement towards the needles, execute an additional lateral movement serving to position the thread.

40 In consequence thereof it is possible without the aid of special mechanism, but merely by means of the latch compressors, to first cause the positioning of the back thread in a manner suitable for the formation of 45 the loop and then after the thread has passed beneath the latch to cause the closing of the latter so that the thread embraced by said latch will be drawn through the loop formed by the front or needle thread.

50 The present invention affords the advantage of doing away with special guiding devices, as is necessary in former constructions, and avoids the drawbacks of the latter arising from such special mechanism, by

providing the upper part of the latch compressor with a laterally projecting thread guiding eye, which on lateral removal of said latch compressor and thus also of the thread-guides, places the back thread very safely over the stem of the hook-shaped catch. If the lateral movement is continued and the catch moves downwards, then the thread placed over the stem of the hook or crochet needle is entered below the latch and the latter is closed.

In the accompanying drawing the invention is illustrated in a diagrammatical way.

Fig. 1 shows a cross-section of the stitch producing mechanism,

Fig. 2 is the top view corresponding thereto,

Figs. 3, 5 and 7 show different steps of operation, and Figs. 4, 6 and 8 are the top-views of Figs. 3, 5 and 7, respectively.

In the drawing 1 is the fabric to be embroidered, and 2 are the embroidery needles adapted to introduce the front thread 3 into the fabric. Fixed to a bar *a* at the back of the fabric are small rods 4, which in number correspond to the needles and are each provided with a hook-shaped catch 5 having a resilient latch 5'. Attached to a special bar *b* are the same number of vertical rods 6 constituting latch compressors which at their upper part are turned towards the fabric and carry a roller 7, respectively. Furthermore a thread-guiding eye 8 is formed on a small arm 9 at the top part of each rod 6 in such a way that the thread-guiding eye is situated laterally of the roller 7 (Fig. 2). The back thread is conducted through the eye 8.

The operation of the device is as follows:—

The front needle 2 has entered the fabric 1, and on its return forms a loop 3'; this loop 3' is engaged from below by the hook-shaped catch 5 in such a way that it assumes a position laterally of the front needle 2. When the catch 5 has moved upwards into the position shown in Fig. 3, the latch compressor 6, 7 and consequently the thread-guiding eye also will perform a lateral movement and thereby place the thread 10 around the stem of the catch 5, as is apparent from Figs. 3 and 4 of the drawing. However, the latch compressor will make a further lateral movement, to wit will move

so far that the roller 7 thereof will be situated in the plane of the catch 5.

At this moment the latter moves downwards and brings the thread 10 laid around the stem under the latch 5'. On a further downward movement the roller 7 of the latch compressor will, as is to be seen from Figs. 5 and 6, force the resilient latch 5' against the needle-stem and the thread caught under the latch will be drawn through the connecting loop left back by the preceding operation. Suitable taking up of the front thread, that may be effected by a backward movement of the needle 2, will contract the old thread-loop in accordance with the length of the preceding stitch now appearing as crochet-loop at the back side of the fabric. After this operation the thread-guide and the latch compressor move back to their initial position, as is shown from Figs. 7 and 8.

Having now fully described my invention I declare that what I claim is:—

1. In a device for the production of crochet seams and patterns in embroidering machines, the combination with an embroidery needle for introducing a continuous front thread into the fabric, of a hook shaped catch for locking the front thread by a continuous back thread and means for closing the hook of said catch, said latter means being formed with thread guiding means.
2. In a device for the production of crochet seams and patterns in embroidering machines, the combination with an embroidery needle for introducing a continuous front thread into the fabric, of a hook shaped catch for locking the front thread by a continuous back thread, means for closing the hook of said catch and a thread guiding eye on said hook closing means so located that when the latter and said hook are op-

posed to each other said thread guiding eye will be positioned laterally of said hook.

3. In a device for the production of crochet seams and patterns in embroidering machines, the combination with an embroidery needle for introducing a continuous front thread into the fabric, of a hook-shaped catch for locking the front thread by a continuous back thread, means for closing the hook of said catch including a roller directed toward said hook and a thread guiding eye on said hook closing means so located that when said roller and said hook are opposed to each other said thread guiding eye will be positioned laterally of said hook.

4. In a device for producing crochet seams and patterns in an embroidering machine, the combination with an embroidery needle for entering loops of a front thread into the fabric, of a hooked catch for passing a back thread through said loops and thereby locking said front thread and means for locking the hook to said catch, said means being made to simultaneously serve as guide for the back thread.

5. In a device for producing crochet seams and patterns in embroidering machines, the combination with an embroidery needle for entering loops of a front thread into the fabric, of a hooked catch for passing a back thread through said loops and thereby locking said front thread, a movable member having its free end directed to said hooked catch and capable of compressing the hook of said catch to close the latter and a guide carried by said member for said back thread.

In testimony whereof I affix my signature in presence of two witnesses.

AUGUST HERMANN MEYER.
